APPARATUS FOR PUNCHING CARDS FOR FILING SYSTEMS

Milton Effros, Great Neck, N. Y., assignor to Superior Business Machines, Inc., New York, N. Y., a corporation of New York

Application November 16, 1948, Serial No. 60,266

9 Claims. (Cl. 164—112)

This invention relates to apparatus for punching cards for filing systems.

The so-called "key sort" method of arranging large quantities of cards in a predetermined relationship involves a preprinted and prepunched card wherein a plurality of openings are punched adjacent an edge of the cards. Each card is treated individually to form notches from holes already punched in the card adjacent its edge. In every case, the cards, preliminarily provided with the holes at the edge of the card, are prepared by a hand operated punching machine which cuts out the remaining paper adjacent the edge of the card to form a notch. Thus, when a pin is inserted through the aligned openings through the cards, some cards can be removed from the assembly since the notches will not hold on the pin the cards in which they are made, while those cards which still have holes will remain on the pin. This operation, wherein cards having prepunched holes adjacent their edges are provided, and wherein separate notching out of the holes in the cards at the edge is resorted to, is very expensive.

It is an object of the invention to provide apparatus, and the method for utilization thereof, wherein no pre-punching of the cards is necessary, and wherein notches are cut and holes are punched simultaneously and in a single operation throughout the entire edge of the card, wherever required by a predetermined code, and with a single setting of the machine.

Apparatus of the type indicated may be operated so that only selected portions of the edges of a card will be worked upon at a particular operation. Thus, there may be situations in which only a portion of the edge of a card will require the formation of some relation of punched holes and cut notches. Thus, the apparatus may be selectively operated to be effective at only such a distinct area. In such a case, the entire area to be utilized in a sorting operation is punched at a single operation; that is, all of the holes and all of the slots are formed by this single operation, whereas heretofore holes were formed first; then notches were formed by cutting away the rest of the edge of the card forming the hole.

In the machines heretofore used, it was necessary to reduce the number of notches to be formed to a minimum, in order to reduce the number of necessary manipulations of the keys in the slotting machine. It was sought to limit the operation to but a single key, or, at most, two keys, for setting up any particular combination. In the apparatus set forth herein, it is possible to produce, by the operation of a single key, all of the notches and openings requisite for a proper sorting operation, so that the number of operations of the punch involved becomes immaterial.

It is an object of the invention to provide apparatus, and the method of utilization thereof, wherein a code may be utilized involving as many notches as possible, in order that, in the subsequent sorting operations, the number of cards lifted in each manipulation of the sorting pin will be reduced to a minimum. Such apparatus will reduce the number of handling operations for each card, will reduce the number of cards lifted, and, therefore, the volume of cards handled, at each manipulation, and will expedite the sorting operations because less cumbersome and less bulky operations are involved.

It is an object of the invention to provide apparatus for the punching of cards in accordance with the processes here discussed, wherein the card is supported in the punch so that it is completely visible to the operator at

2

all times, and so that the card may be handled from one position to another without any substantial change in the operator's position between the setting up position, the punching position, and the release position, of the card.

5 Other objects of the invention will be set forth hereinafter, or will be apparent from the description and the drawings, in which are illustrated embodiments exemplifying the invention.

The invention, however, is not intended to be restricted to any particular construction, or any particular arrangement of parts, or any particular application of any such construction or arrangement of parts, or any specific method of operation or use, or any of the various details thereof, even where specifically shown and described herein, as the same may be modified in various particulars, or may be applied in many varied relations, without departing from the spirit and scope of the invention, of which the exemplifying embodiment, herein shown and described, is intended only to be illustrative, and only for the purpose of complying with the requirements of the statutes for disclosure of an operative embodiment, but not to show all the various forms and modifications in which the invention might be embodied.

On the drawings, in which the same reference characters refer to the same parts throughout, and in which are disclosed such practical constructions,

Fig. 1 is a detail vertical cross-sectional view longitudinally of a machine embodying features of the invention;

10 Fig. 2 is a plan view of the machine shown in Fig. 1, illustrating details of the various operating members;

Fig. 3 is a perspective view of a set of levers which enter into the operation of the apparatus, the spacing of the levers being exaggerated;

15 Fig. 4 is a plan view of a card produced by the machine of Fig. 1;

Fig. 5 is a detail view to enlarged scale, to illustrate the relationship between hole and notch, as produced by adjusting the position of the punches;

20 Figs. 6, 7, 8 and 9 are detail elevational views of portions of the operating mechanism; and

Fig. 10 is a diagram to illustrate the relation in timing of the various cams.

On the drawings, there is illustrated apparatus 10 for effecting the purposes of the invention. Apparatus 10 may consist of a casing 12 having a partition wall 14 located to provide a support for a sloping wall 16 which extends from wall 14 down to a front wall 18 and a footing wall 20.

25 Supported between partition wall 14 and end walls 22 is a housing wall 24. The wall 26 of casing 12 may be formed to provide a slot 28 by indenting a portion of the wall downwardly and cutting to form edges 30.

A card 32, inserted through slot 28, comes to rest in the groove 34 formed by notches 36 in the bodies of a plurality of dies 38. These dies are assembled, in side by side relationship, between housing wall 24 and a die retaining wall 40, so that the notches are in alignment and form groove 34. Wall 40 may be assembled with

30 housing wall 24 in any suitable manner, as, for instance, by bolting or welding. The top edges 42 and 44 of walls 24 and 40 may have means for retaining the dies in place, as, for instance, by being flanged inwardly to form retaining walls 46 which serve to limit upward movement of dies 38.

35 Each die tends to move upwardly under the action of an individual spring 48 received around post 50 upon which the die is secured. The post extends downwardly from the die through aligned openings 52 and 54 in wall 40 and bottom wall 56 of housing wall 24, respectively. Spring 48 is retained by a suitable pin 58 fixed in post 50 and against wall 56 in order resiliently to drive the particular die 38 normally into engagement with walls 46.

40 Each die may be formed with a passage 60 in which is positioned a punch 62. Immediately at notch 36, passage 60 is enlarged to provide an additional recess 64 to receive the edge of card 32 so that normally the card will, when resting in recess 64, cooperate with punch 62 for the formation of a hole 66, such as shown in Fig. 4, inwardly spaced from edge 68. Beyond recess 64, passage 60 continues for a short distance at the diameter to co-

operate with the punch, and then widens, as at 70, to provide for the reception of punchings from the die and for their discharge through an opening 72 in housing wall 24. These punchings may be received in a chamber 74 defined between walls 24 and 26, and may be removed through a drawer or similar access providing means 76.

Each punch 62 is carried by its die and includes an arm which extends through a slot 80 formed in wall 40. Each arm terminates in a bent up end 82 which extends into a recess 84 provided in a cam 86. Cam 86 and the recess formed therein extend the length of the casing to engage the ends 82 of all of the punches.

Each die 38 and, therefore, its associated punch 62 and end 82 are capable of limited vertical movement away from walls 46 and with relation to the housing provided by walls 24 and 40. During such vertical movement, the end 82 moves within recess 84; it is limited in its movement so that it never moves out of that recess. When cam 86 is rocked along a longitudinal axis, it remains always in engagement with ends 82, and thus will operate every one of the ends, no matter what the adjusted vertical position of each of the dies may be.

Carried upon top wall 26 are a pair of trays 90 and 92 for the reception of cards to be worked upon by the operator. For instance, the operator may position upon tray 90 a plurality of cards, each bearing data which will control its punching. A card is taken from tray 90, placed in groove 34 and punched. Then it may be removed from groove 34 and placed upon cards stacked on tray 92. The cards on tray 90 are disposed so that data on them is visible to the operator so that proper manipulation of keys 94 may be effected.

Carried by each post 50 is a pin 96 which fits into a slot 98 in an arm 100 of a bell crank 102. Crank 102 is pivotally mounted on a pin 104 which extends through the casing between its end walls. The end of the other arm 106 of the bell crank is pivotally connected with a link 108 which extends through and is slidably supported in a slot 110 in footing wall 20. Allowance is thus made for slight reciprocal and vertical movement of link 108 as it moves to actuate crank 102 and is moved by the actuating means.

It is intended to punch the cards according to a predetermined code to accommodate certain combinations of characters. For this purpose, it is necessary to utilize more than one link and, therefore, more than one punch and die, for any code number or combination of symbols. Where it is desired to utilize a code based upon the numerical system, a combination such as shown in Fig. 3 may be utilized. In that case, four links 108, 112, 114 and 116 are arranged to set up the symbols which are to be made to appear upon the card at, for instance, an area 118 which, for example, will be taken to encompass the series of units of a combination of numbers of three figures. In other words, there will have to be three distinct areas 118 each of which will have four links 108, 112, 114 and 116. The links are thin enough to be positioned snugly side by side, and not to require more than the spacing for a set of keys 94 positioned in a row 120.

Each key has a button 122 which, by its cooperation with an opening 124 in a wall 126 forming the outer wall of the casing, serves to guide the key in its vertical movement. Each button has a pin 128 extending therefrom, the pin being secured to the button so as to be substantially rigid therewith. A spring 130 is carried by the pin between the button and a ledge formed in wall 16 for that purpose. The spring tends to drive button 122 through opening 124 to its upper limit determined by another pin 132. Pin 132, also carried by button 122, extends down through an opening 134 formed in wall 16, and has a bent end 136 to engage the bottom face of wall 16 at the opening, to limit movement of the button and retain it against separation from the casing. End 136 has a lateral extent sufficient to engage selected ones of a plurality of cam faces 138 formed on projections from the respective links 108, 112, 114 and 116, in accordance with the particular button involved, and also to engage under a short notch or finger 140 on the particular projection at the lower end of each face 138.

As button 122 is depressed, its end 136 will engage the particular cam or cams 138 on selected links, according to the code, and will cause the links to slide downwardly through their slots 110. At the end of the movement of the button, end 136 will catch in the notch or notches 140, and thus serve to retain the link or links in the posi-

tion to which they have been projected, and, of course, at the same time, hold the button down, indicating the code number which is to be punched. Springs 48 and 130 are in compression, holding the parts in these positions. If it is desired, before punching, to clear one of the numbers the button for which has been depressed, and to position some other number, it is only necessary to press any one of the other buttons in that particular line. The end 136 of the new button will engage against the new face 138, moving the particular link through slot 110, and thus causing the end 136 previously caught in a notch 140 to be released. Continued movement of that button last actuated will bring its particular end 136 into engagement with the notches therewith associated, and the associated links will be locked in position. A cam 142 is also provided which, on operation by suitable means, will engage an arm 144 carried by each link. Movement of the links will cause release of all of the engaged buttons. Thereafter, new buttons may be manipulated individually. Individual clearing buttons 146 are provided for each row. The links 108, 112, 114 and 116 of each set have cams 148. Manipulation of a button 146 will cause all of the links of a particular area to be repositioned.

It will be noted that the code is arranged, in the instance disclosed, so that the largest number of links are actuated for each setting, thereby obtaining depression of as many dies as possible, within the code, for each setting. This is in contradistinction to the procedure previously followed wherein the hand operator merely punched one or, at most, two holes for slotting out holes preliminarily punched, within the code. For instance, for the character 9, all four faces 138 on the associated links 108, 112, 114 and 116 are to be engaged by the end 136 for the button at that position; therefore, all of the links will be set to move the dies associated therewith to the lowered position.

Since, however, by such an operation, there always will be at least one or two dies or an end member provided for that purpose positioned to retain the card in the position it retains in Fig. 1, where the dies are in the normal position, the card will remain at the same vertical position shown, even though some of the dies have been moved to the lower vertical position. When the dies are moved to the lower position by proper manipulation of a link or all of the links, the associated punch 62, in the case of a die which has been lowered, is in line not to punch a hole within the edge, but to cut off the edge of the card. In other words, hole 66 will not be formed, but a slot 150 will be formed. Since, for a character 9 in the combination shown in the drawings, all of the links have been depressed, all of the cuttings at the edge of the cards will be slots 150.

If any button for the other numbers had been actuated by the depression of the proper button, less than all of the links would have been moved. In that case, as, for instance, in connection with the number 8, link 108, which has no cam face 138 at that position, would be clear. The punch and die associated with that link would, therefore, form a hole 66 not extending to the edge of the card; this can be called the first position. All of the other punches and dies, being depressed, would form slots.

In the same manner, for the number 7, link 112 would not be moved on actuation of the button for that member. A hole would, therefore, be formed at the position of this link, which may be termed the "second" position, but all the punches associated with the other links would form slots. For the number 6, links 108 and 112 would not be disturbed, so that holes would be formed at both the first and second positions, but slots would be formed at the third and fourth positions. In connection with the number 5, link 114 would not be actuated. Therefore, slots would be formed at all positions but the third, where a hole would be formed. In connection with the number 4, links 112 and 114 would not be actuated. Thus, holes would be formed at the second and third positions, but slots would be formed at the first and fourth positions. In connection with the number 3, link 116 would not be actuated. Thus a hole would be formed only at the fourth position. In connection with the number 2, holes would be formed in connection with links 108 and 116, which would not be actuated. In connection with the number 1, holes would be formed at the

third and fourth positions because links 114 and 116 would not be actuated.

The result from a situation such as this is that when cards punched according to this system are set up for separation by means of the insertion of a pin, or "needle," as it is sometimes called, through the aligned openings, and if the needle is first inserted through the holes at the first position, and the needle is lifted, since slots are formed for the numbers 1, 3, 4, 5, 7 and 9, only the cards cut for the code numbers 2, 6 and 8 will be lifted. In other words, only cards within one-third of the range of the code will be lifted. Under the old system, it is practically impossible to lift less than two-thirds. Thus, by this process a smaller number of cards are lifted at the first position. The cards so lifted are placed at the front of the cards which were not lifted. This means that cards punched with holes for numbers 2, 6 and 8 would be positioned in front of all the others.

Now when the needle is inserted at the second position, only the cards at the position for the numbers 4, 6 and 7 will be lifted. Again there are only three numbers lifted. However, in the old combination, at the second position, cards for the numbers 1, 4, 5 and 7 would be lifted; and, again, only those cards which were dropped would be handled, and not the cards which were on the pin. The cards for the numbers 4, 6 and 7 are now placed at the front. But it will be noted that they have taken the arrangement where those of the number 6 are in front of the group for both numbers 4 and 7, while the group for the numbers 2 and 8 are just behind those of the numbers 4 and 7, while those for the numbers 1, 3, 5 and 9 now end the assembled cards.

Now, at the third position, again there are only three numbers lifted, that is, 1, 4 and 5. Again the lifted cards are placed at the front.

The arrangement now is such that those for the number 4 are separated, and are followed by those in the group of the numbers 1 and 5, which then are followed by those for the number 6, then by those for the number 7, then by those for the group of numbers 2 and 8, and finally by those for the group of numbers 3 and 9.

Now, at the fourth position, only cards for three numbers are lifted, those corresponding to the numbers 1, 2 and 3. They are positioned at the front of the pack. Now the cards will be found to be in exact order.

In other words, the sorting would follow a scheme as follows, wherein the underlined numbers indicate the one lifted, and the brackets indicate groups within which the cards are not necessarily arranged in the order given:

1. (2, 6, 8) (1, 3, 4, 5, 7, 9)
2. (6), (4, 7) (2, 8) (1, 3, 5, 9)
3. (4), (1, 5) (6) (7) (2, 8) (3, 9)
4. (1), (2), (3), (4) (5) (6) (7) (8) (9)

It has been found in handling that a procedure in which a number of cards are discarded from and have to be shaken out of the pack is inefficient since cards tend to stick within a mass of cards. Where cards are lifted out of a mass in order that they be separated, cards do not tend to stick to the other cards as they slide out of the mass. The necessity for shaking cards out of a mass is not conducive to a proper separation.

The apparatus may be made automatic for continuous operation by an electric motor drive. In such case, power for driving the apparatus is transmitted from a proper motor (not shown), and is brought up to a shaft 152 by means of a belt 154 trained around pulleys 155 and 158, the last of which is secured to shaft 152. Shaft 152 is provided a bearing in a suitable support 160 positioned in any desirable manner within casing 12. A bearing for shaft 152 may be provided in a bore within a stub shaft 164 which may be carried in supports 162 and 166.

Affixed to pulley 158 is a disc 168, which has a plurality of peripheral notches 170 intended to receive a tooth 172 at the end of a finger 174. The finger is pivotally mounted at the end of an arm 176 which is fixed on shaft 164. Arm 176 and finger 174 have associated ends 178 and 180 which extend so as to seat in a notch 182 in an actuating bar 184. Bar 184 is pivoted at a position 186 in the casing so that it may be depressed against the action of a spring 188 by pressing against a plate or bar 190, above wall 126. Upward movement of

bar 190 is limited by engagement of a tooth 192 against the under side of wall 16.

When pulley 158 is rotated, disc 168 also is rotated. However, by reason of the engagement of ends 178 and 180 in notch 182, tooth 172 is held out of position, so that spring 194 will not move the finger into engagement with any one of the notches 170. On depression of bar 190, notch 182 is moved out of the way of ends 178 and 180; spring 194 moves tooth 172 against the face of disc 168, so that it will engage the next notch 170 which comes into position as the peripheral edge of disc 168 rides past tooth 172. With tooth 172 engaged in a notch 170, rotational movement is imparted to arm 176. Arm 176, affixed to shaft 164, causes that shaft continuously to rotate until ends 178 and 180 reach and ride up on a spring pressed finger 196, pivoted on bar 184, the end face of which functions as one wall of notch 182. Finger 196 is depressed by ends 178 and 180 until they ride past the end of the finger and come to rest against the fixed wall 198 of notch 182. Tooth 172 is forced out of the notch 170 in which it is engaged, and movement of arm 176, and thereby of shaft 164, is stopped.

On shaft 164 is disposed an eccentric 200 with which is carried an eccentric strap 202, which in turn forms a part of a link 204 pivotally connected with a crank 206. Crank 206 is fixed to a shaft 208 on which cam 86 is mounted. Thus, for each actuation of bar 190, parts will be set in motion to cause a single oscillation of cam 86, and thus of all of the punches at every position, and regardless of their individual adjustments, which will simultaneously be operated by the cam.

In supports 210 bearings are provided for a shaft 212 upon which is secured cam 142. Shaft 212 is permitted limited axial movement through its bearings, a spring 214 bearing against the bearing at one end to move the cam and the shaft so that a slotted end 215 normally will tend to engage with a spline end 216 on stub shaft 164. A forked arm 218, pivotally mounted on a bracket 220, is mounted so that the other end 222 of the crank of which it forms a part may be engaged by the rod 224 of a repeat button 226. A spring 228 normally tends to project button 226 above wall 126. A slot 230 in the side of the button may be engaged with an edge 232 of opening 234 in wall 126, so that the button may be retained in the depressed position, as shown in Fig. 8. When button 226 is moved to this depressed position, shaft 212 and cam 142 carried thereby are moved to the left, in Figs. 6 and 8, and thus break the interlocked connection between ends 215 and 216. Cam 142 is then not driven by the actuating motor; thus repeated actuations of bar 190 will produce repeated actuations of the same settings of the punches. When button 226 is not depressed, cam 142 will function to clear the settings of members 108, 112, 114 and 116, to be ready for a new setting.

As shown in Fig. 10, the timing for movements of the shafts 208 and 212 is such that the punches, being rocked by crank 206 (the cycle shown at the top of the curve) will have completed their punching action (shown by the portion of the curve below the axis), in their movement into the die, and will have moved away to a position where the punch will have moved out of the hole formed in the card so that the card may be removed from the apparatus, before cam 142 will be rotated to engage arm 144 (shown by angular portion of the bottom line). Thus, the assembled punches and dies may move relatively to the card, upon release of the individual links, since the punches will no longer be engaged through the cards so that there will be no tearing action upon the cards.

In view of the force required for actuation of the punches, it is desirable that a pair of links 204 and a pair of cranks 206, one at each end of shaft 208, be utilized for transmitting force from shaft 164 to shaft 208. For this purpose, a countershaft 236 is carried by bearings provided in the casing. By means of gears 238 at one end and gears 240 at the other end of countershaft 236, a short shaft 242 has rotation imparted thereto from shaft 164. Bearings are provided for shaft 242 in supports 243; shaft 242 carries an eccentric 200, which, through a suitable eccentric strap, moves a link 204 which is connected to a crank 206 at the opposite end of shaft 208 removed from the associated members driven directly by shaft 164.

Many other changes could be effected in the partic-

ular construction, and in the methods of use and construction, and in specific details thereof, hereinbefore set forth, without substantially departing from the invention defined in the claims, the specific description being merely of embodiments capable of illustrating certain principles of the invention.

What is claimed as new and useful is:

1. In a device for forming a series of slots, holes, or a selected association of them, at the edge of a card or like sheet material, the device including a plurality of punch-and-die assemblies, each assembly including a punch movable with respect to the die to interfit with and move out of interfitting relation to the die, the assembly providing means for receiving and supporting a card or the like edgewise for working thereon, the assemblies being positioned substantially in laterally contiguous relationship and being movable relatively to each other, means for retaining the assemblies in a normal position for making one type of cut in the card, individual setting means for each assembly for adjusting the assembly out of supporting relation to the edge of the card to make another kind of cut in the card, and single means for actuating all of the assemblies simultaneously to form holes or slots according to the position of the several individual setting means.

2. In a device for forming a series of slots, holes or a selected association of them, at the edge of a card or like sheet material, the device including a plurality of punch-and-die assemblies, each assembly including a punch movable with respect to the die, the assembly providing means for receiving and supporting a card or the like edgewise for working thereon, means for retaining the assemblies substantially in alignment with each other so that the card-receiving means functions as a single unit for supporting a card edgewise, means for moving each assembly individually to a position with relation to the edge of the card out of the supporting position, means for retaining in the positions to which they have been moved those assemblies for which the moving means have been actuated, and single means for actuating all of the assemblies simultaneously to form holes or slots according to the position of the several individual setting means.

3. In a device for forming a series of slots, holes, or a selected association of them, at the edge of a card or like sheet material, the device including a plurality of punch-and-die assemblies, each assembly including a punch movable with respect to the die to interfit with and move out of interfitting relation to the die, the assembly providing means for receiving and supporting a card or the like edgewise for working thereon, the assemblies being positioned substantially in laterally contiguous relationship and being movable relatively to each other, means for retaining the assemblies substantially in alignment with each other so that the card-receiving means functions as a single unit for supporting a card edgewise, means for moving each assembly individually to a position with relation to the edge of the card out of the supporting position, means for retaining in the positions to which they have been moved those assemblies for which the moving means have been actuated, single means for actuating all of the assemblies simultaneously to form holes or slots according to the position of the several individual setting means, and means for releasing the retaining means immediately upon the completion of operation of the single actuating means.

4. In a device for forming a series of holes or slots, or a selected association thereof, at the edge of a card or like sheet material, the device including a plurality of sets of assemblies, each assembly being movable substantially vertically and including a slot opening upwardly, means for maintaining the assemblies in a normally raised position in which the slots are in alignment for receiving a card or the like edgewise, means for sustaining said card or the like in a vertical position, means for lowering the assemblies individually out of the normally raised position, each assembly including a die, and a punch movable transversely of the direction of the assembly movement on lowering, selective means for actuating selected ones of the individual lowering means, a rock bar mounted on a fixed axis, each of said assemblies having a punch-actuating member, and means coupling said rock bar to said members so that, on actuation of the rock bar, all of the assemblies are actuated whether in the normally raised or in the

lowered position, the assemblies in the normally raised position producing, on actuation of the rock bar, holes in the card, and in the lowered position, slots in the edge of the card.

5. In a device for forming a series of holes or slots, or a selected association thereof, at the edge of a card or like sheet material, the device including a plurality of sets of assemblies, each assembly being movable substantially vertically and including a slot opening upwardly, means for maintaining the assemblies in a normally raised position in which the slots are in alignment for receiving a card or the like edgewise, means for sustaining said card or the like in a vertical position, means for lowering the assemblies individually out of the normally raised position, each assembly including a die, and a punch movable transversely of the direction of the assembly movement on lowering, selective means for actuating selected ones of the individual lowering means, but less than the whole number of such individual lowering means for any set, a rock bar mounted on a fixed axis, each of said assemblies having a punch-actuating member, and means coupling said rock bar to said members so that, on actuation of the rock bar, all of the assemblies are actuated whether in the normally raised or in the lowered position, the assemblies in the normally raised position producing, on actuation of the rock bar, holes in the card, and in the lowered position, slots in the edge of the card.

6. In a device for forming a series of holes or slots, or a selected association thereof, at the edge of a card or like sheet material, the device including a plurality of sets of assemblies, each assembly being movable substantially vertically and including a slot opening upwardly, means for maintaining the assemblies in a normally raised position in which the slots are in alignment for receiving a card or the like edgewise, means for sustaining said card or the like in a vertical position, means for lowering the assemblies individually out of the normally raised position, each assembly including a die, and a horizontally movable punch, selective means for actuating selected ones of the individual lowering means, a rock bar mounted on a fixed axis, each of said punches having an arm, and means for maintaining positive drive coupling between the arms and the rock bar as the assemblies are moved into and out of their several positions so that, on actuation of the rock bar, all of the assemblies are actuated whether in the normally raised or in the lowered position, the assemblies in the normally raised position producing, on actuation of the rock bar, holes in the card, and in the lowered position, slots in the edge of the card.

7. In a device for forming a series of holes or slots, or a selected association thereof, at the edge of a card or like sheet material, the device including a plurality of sets of assemblies, each assembly including a die having a slot opening upwardly, means for supporting the die to be capable of vertical movement, means for causing the supporting means to move the dies to a normally raised position in which the slots are in alignment for receiving a card or the like edgewise, means for sustaining said card or the like in a vertical position, means for lowering the dies individually out of the normally raised position, each die having a punch movable substantially horizontally in the die, selective means for actuating selected ones of the individual lowering means, a rock bar mounted on a fixed axis, each punch having a member extending therefrom, and means coupling said rock bar to said members so that, on actuation of the rock bar, all of the assemblies are actuated whether in the normally raised or in the lowered position, the assemblies in the normally raised position producing, on actuation of the rock bar, holes in the card, and in the lowered position, slots in the edge of the card.

8. In a device for forming a series of holes or slots, or a selected association thereof, at the edge of a card or like sheet material, the device including a plurality of sets of assemblies, each assembly being movable substantially vertically and including a slot opening upwardly, means for maintaining the assemblies in a normally raised position in which the slots are in alignment for receiving a card or the like edgewise, means for sustaining said card or the like in a vertical position, means for lowering the assemblies individually out of the normally raised position, each assembly including a die, and a punch movable transversely of the direction of the

assembly movement on lowering, selective means for actuating selected ones of the individual lowering means, a rock bar mounted on a fixed axis, each of said assemblies having a punch-actuating member, and means providing a loose coupling between the rock bar and said members, the loose coupling means including a recess in the bar and an end on the member nested in the recess so that, on actuation of the rock bar, all of the members are actuated whether the assemblies are in the normally raised or in the lowered position, the assemblies in the normally raised position producing, on actuation of the rock bar, holes in the card, and in the lowered position, slots in the edge of the card.

9. In a device for forming a series of holes or slots, or a selected association thereof, at the edge of a card or like sheet material, the device including a plurality of sets of assemblies, each assembly including a die having a slot opening upwardly, means for supporting the die to be capable of vertical movement, means for causing the supporting means to move the dies to a normally raised position in which the slots are in alignment for receiving a card or the like edgewise, means for sustaining said card or the like in a vertical position, means for lowering the dies individually out of the normally

raised position, each die having a punch movable substantially horizontally in the die, selective means for actuating selected ones of the individual lowering means, a rock bar mounted on a fixed axis, each punch having a member extending therefrom, and means providing a loose coupling between the rock bar and said members, the loose coupling providing means positively to maintain drive coupling between the members and the rock bar at all times as the assemblies are moved into and out of their several positions so that, on actuation of the rock bar, all of the assemblies are actuated whether in the normally raised or in the lowered position, the assemblies in the normally raised position producing, on actuation of the rock bar, holes in the card, and in the lowered position, slots in the edge of the card.
